UNITED STATES PATENT OFFICE.

HENRY W. MASON AND PATRICK CUNNINGHAM, OF NEW BEDFORD, MASS.

MOUNTING BOAT-GUNS.

SPECIFICATION forming part of Letters Patent No. 269,080, dated December 12, 1882.
Application filed January 12, 1880.*To all whom it may concern:*

Be it known that we, HENRY W. MASON and PATRICK CUNNINGHAM, of New Bedford, in the county of Bristol and State of Massachusetts, have invented a new and useful Improvement in Apparatus for Taking Whales, of which the following is specification.

Guns have been constructed for the purpose of firing a harpoon into a whale from a distance; but when such guns are of sufficient weight to throw a harpoon a sufficient distance the recoil of the gun is so great as to seriously injure the boat, and make it extremely dangerous to the life of the man who fired it. Explosive harpoons have been made to be fired from a shoulder-gun; but they have of necessity been made so small (on account of the recoil being so great in firing a heavier projectile) that the killing of a whale could not be assured.

The object of this invention is to provide a gun which can be used in killing whales from a safe distance, and also be easily and safely used without the least injury to the boat or danger to the person using it.

This invention consists in the particular construction of a gun with which to fire the harpoon and bomb; also in the arrangement of the gun on its pivot, in connection with springs of suitable material, and the use of springs at the points of contact of the pivot and its supports, whereby the effects of the recoil of the gun on the boat are obviated.

In the accompanying drawings, in which similar letters of reference indicate like parts, Figure 1 is a perspective of the gun mounted in the bow of a whale-boat, ready for use. Fig. 2 is a top view of the gun G and the casting C, and also showing a horizontal longitudinal section of the left-hand trunnion and spring. Fig. 3 is a sectional view of the box E.

In the "clumsy cleat" B of the boat A is fixed the box E, the construction of which will readily be seen by reference to Fig. 3, in which the parts e and f are of metal, and d' is of rubber or other elastic substance, for a purpose hereinafter mentioned. Through the box E the pivot or standard D passes and extends to D', where it enters a hole in the floor of the boat. To the top of the pivot D is affixed the casting C, in which casting is hung by its trunnions the gun G.

The construction of the casting C and the manner of hanging the gun G will readily be seen by reference to Fig. 2, in which is shown a sectional view of the left-hand trunnion and spring.

b b are the trunnions, which are secured into the sides of the gun G, the gun being supported by them on the slides a a, said slides passing through perforations made for the purpose in the outer ends of the trunnions.

To the rear of the trunnions, and around the slides a a, are placed the springs d d, of rubber or other suitable material, for a purpose hereinafter mentioned.

The operation of the apparatus is as follows: The breech-block of the gun G is opened, a cartridge inserted, and the breech-block closed. The harpoon H, with line attached, is then loaded into the muzzle of the gun and crowded home. The gun is then fired. As the harpoon, which we shall construct as a bomb lance or harpoon, leaves the gun, a lanyard, which will be attached to the wire of the bomb-primer and to the gun, will draw the wire from the primer, (thus lighting the fuse of the bomb,) so that a few moments after the harpoon enters the whale the shell, being filled with powder, explodes, driving the shank of the harpoon a short distance to the rear, when the points of the rings h' catch in the flesh and open, thus killing and fastening to the whale at the same time. When the gun is fired the force of the recoil is caught on the cushions or springs d d, as shown in Fig. 2, and partially by the cushion or spring in box E, thus converting the sudden blow of a recoil into a push. By the use of these cushions or springs the boat is entirely relieved from danger of injury from the recoil, as is also the person firing the gun.

By the use of a cartridge the operation of loading is performed so quickly that sometimes a number of whales can be killed before they get out of reach.

We are aware that it is old, broadly, to employ, in connection with the trunnions of a gun, elastic cushions or springs arranged in rear of said trunnions, and to support the gun upon an upright stud or short post arranged between springs.

Having thus described our invention, what we claim is—

BEST AVAILABLE COPIE

2

269,080

In a boat, the combination, with its clumsy bar B, having the box E, with an elastic cushion or spring, d', arranged between its two parts, and one of said parts adapted to slide 5 at one end upon the other, of the standard D, having the casting or box C, provided with rods a, upon which are arranged elastic cushions or springs d, and a gun having its trunnions b fitted to slide upon the rods a in front of the springs d, substantially as described.

HENRY W. MASON.
